UNITED STATES PATENT OFFICE

2,526,485

DUST MOP CLEANER

Leonard R. Kortick, Providence, R. I.

Application November 8, 1946, Serial No. 708,687

2 Claims. (Cl. 15—310)

1

My present invention relates to dust extractors, and more particularly to a novel apparatus for extracting dust from a dry mop.

The principal object of the present invention is to provide an appliance for extracting dust from a dry dust mop.

Another object of the present invention is to provide a dust mop cleanser which will prevent the dust from escaping and which will eliminate shaking out the mop.

A further object of the present invention is to provide an appliance which may be used independently or as an attachment to a conventional vacuum cleaner.

With the above and other objects and advantageous features in view, my invention consists of a novel arrangement of parts, more fully disclosed in the detailed description following, and more particularly defined in the appended claims.

In the drawings:

Fig. 1 is a perspective view of an apparatus embodying my invention;

Fig. 2 is a section taken on line 2—2 of Fig. 1;

Fig. 3 is a section taken on line 3—3 of Fig. 2, with the drawer 37 removed;

Fig. 4 is a section taken on line 4—4 of Fig. 3;

Fig. 5 is a perspective view of another form of my invention;

Fig. 6 is a section taken on line 6—6 of Fig. 5;

Fig. 7 is a section taken on line 7—7 of Fig. 6, with the drawer 46 removed;

Fig. 8 is a section taken on line 8—8 of Fig. 6;

Fig. 9 is a perspective view of another form of my invention; and

Fig. 10 is a section taken on line 10—10 of Fig. 9.

Cleaning the dust mop is a nuisance to the housewife. Most people shake out the dust, out of a window or in the back yard, creating a nuisance to themselves and the neighbors. The present invention is designed to provide means for extracting dust from a mop cleanly and efficiently. The device is simple in construction, easy and economical to manufacture and assemble, and simple to operate.

Referring more in detail to the drawings illustrating my invention, the form of my invention shown in Fig. 1 comprises a housing 20 which may be of any desired shape but is preferably circular in cross-section, as illustrated. The housing 20 has a wide flared bottom edge 21 to give it stability, and a domed top 22. Referring to Figs. 2 and 3, the interior of the housing 20 is divided into upper and lower por-

tions 23 and 24 by an annular flange 25 fixed to the interior of the housing. A heavy wire wide meshed screen 26 is mounted on the flange 25 and is provided with upstanding rubber nipples 27 at each intersection of the wires.

One side of the dome 22 is cut out, as at 28, to form an opening which is covered by a door 29 slideable inside of the dome. The door 29 tapers upwardly beyond the center of the dome 22 and is pivoted on a screw 30. A coil spring 31 is mounted on the screw 30 with its free end bearing against a pin 32 on the door 29 to normally retain the door in closed position. The door 29 slides between the housing 20 and a flange 33 mounted on the flange 25 (Figs. 2 and 3).

The front edge of the dome opening 28 is cut out in a semi-circle and the door 29 is cut out in a complementary manner to form a circular opening 34 in the front of the dome. The door 29 is also provided with a raised portion 35 which acts as a finger hold for sliding the door open against the action of the spring 31. The lower portion 24 of the housing is cut out in front in a rectangular opening 36. A flat circular drawer 37, Fig. 4, is slideable within the opening to fill the lower portion 24. The drawer 37 is provided with a conventional pull knob 38 at the front wall. It should be noted that the opening 36 is just short of extending half way around the housing 20 so that the drawer 37 will snap into position and will be retained in place by the side wall of the housing.

To shake out a mop, the door 29 is slid open by pushing the portion 35 against the action of the spring 31. The mop (dotted lines in Fig. 2) is then placed into the upper portion 23 of the housing 20 over the screen 26 and nipples 27. The door 29 is allowed to swing shut, the mop handle extending through the opening 34. The mop is now agitated and rubbed across the nipples 27, the dust falling through the mesh 26 into the drawer 37 from which it can be emptied at leisure.

If a more thorough dust extraction is desired, the forms shown in Figs. 5 to 10 inclusive may be used. The form shown in Figs. 5 to 8 is similar to the one in Figs. 1 to 4. It comprises a similar housing 39 with a screen 40 and nipples 41 mounted on a flange 42 dividing the housing 39 into upper and lower portions 43 and 44. The upper portion is also provided with a spring pressed door 45. However, instead of the drawer 37, this form is provided with a circular drawer 46 having a bottom 47 which curves from the

upper rear edge downwardly towards the front (Fig. 6). The front is flared outwardly to form a protruded opening 48 in which a short pipe section 49 is mounted. The pipe 49 has a pin 50 at one side for a bayonet attachment with a vacuum cleaner hose.

This form can be used similarly to the one shown in Fig. 1. However, the hose of a conventional vacuum cleaner can be attached to the pipe 49 and the mop may be agitated over the nipples and subject to the suction action of a vacuum cleaner. This provides a thorough extraction of the dust from the mop.

In the form shown in Figs. 9 and 10, the housing 51 is generally oval in shape. The front portion is similar to the previous forms with a domed top 52 having a spring pressed door 53. The front section is also provided with the screen 54 and nipples 55. The drawer 56 has a bottom 57 similar to the drawer 46 except that it curves from the top of the front edge downwardly and rearwardly to an opening 58 in the rear. The opening 58 has an extending pipe 59 which fits into a vacuum cleaner 60 mounted in the rear portion of the housing 51. The small vacuum cleaner 60 has a conventional bag 61 which can be emptied by opening the cover 62 in the rear portion of the housing. This form can be used similarly to the two previous forms or the vacuum can be turned on to provide the suction as in the second form.

While I have described certain specific embodiments of my invention, it is obvious that changes may readily be made in the size, shape and relative arrangement of parts, without departing from the spirit and scope of my invention as defined in the appended claims.

I claim:

1. In a device of the character described, a housing, an open wire mesh separating said housing into upper and lower chambers, an upstanding solid rubber nipple fixed to each inter-

section of said wire mesh, a door in said upper chamber to permit the insertion of a dust mop, a spring normally urging said door into closed position, said door and housing having an opening to accommodate the mop handle, and a removable drawer in said lower chamber, whereby agitation of said mop over said nipples causes dust to drop through said mesh into said drawer, said drawer having means for connecting said drawer to a suction cleaner.

2. In a device of the character described, a housing, an open wire mesh separating said housing into upper and lower chambers, an upstanding solid rubber nipple fixed to each intersection of said wire mesh, a door in said upper chamber to permit the insertion of a dust mop, a spring normally urging said door into closed position, said door and housing having an opening to accommodate the mop handle, a suction cleaner in said housing adjacent said lower chamber, and a removable drawer in said lower chamber, whereby agitation of said mop over said nipples causes dust to drop through said mesh into said drawer, said drawer being connected to said suction cleaner.

LEONARD R. KORTICK.
